UNITED STATES PATENT OFFICE.

JEAN ZWICKY, OF SOUTH TOTTENHAM, ENGLAND.

PUMP AND COMPRESSOR.

1,339,311.

Specification of Letters Patent.

Patented May 4, 1920.

Application filed June 13, 1917. Serial No. 174,577.

To all whom it may concern:

Be it known that I, JEAN ZWICKY, a subject of the King of Great Britain and Ireland, residing at 66 Chester road, South 5 Tottenham, in the county of Middlesex, England, have invented new and useful Improvements in Pumps and Compressors, of which the following is a specification.

This invention relates to pumps and compressors, and in particular to improvements upon and further developments of the constructions described in my former U. S. Patent No. 1203682. Those constructions comprised two working cylinders in axial 15 alinement with a piston in each upon a common piston rod, and with ports and means controlling them located between the cylinders, the ports allowing egress from the cylinders on all sides. In certain of 20 these constructions the port controlling means comprised spring pressed valves in combination with a reciprocating member covering or uncovering ports upon a cylindrical surface.

25 By my present invention I am enabled further to simplify the construction of pumps and the like of this class by dispensing with the reciprocating member and controlling both inlet and outlet ports for 30 both cylinders by means of disk valves; and moreover to do so while still retaining the advantage of the co-axial cylinders with ports and port controlling means located between them.

35 One main purpose of my invention, therefore, is the provision of a valve structure to be located between two cylinders which will control ingress into and egress from each of the cylinders by means of disk valves 40 affording the fluid as direct and unencumbered a path as possible. By this provision I obtain a pump capable of dealing with liquids that are muddy, or otherwise contain solid particles.

45 Such a valve structure is made without involving complicated castings or any difficulty in assembling by constructing it in two concentric parts. Inner ported members which carry the disk valves are 50 rounded by a junction member or ring which completes channels with as little restriction as possible between the annular ports and lateral inlet and outlet openings.

I have also held in view in the further 55 development of this pump the desirability of enabling the pump to be readily assem-

bled and therefore readily taken to pieces when necessary. Both my central valve structure and also my whole pump in the most improved form are capable of ready 60 assembly with a minimum number of bolts or studs.

It has been a further object of my former inventions to reduce, as far as possible, the number of fluid-tight joints, especially sliding or moving joints, that the pump or the like requires; which end has been largely attained by the location of a double set of valves between two pistons. By the addition of a further set of valves and a fixed 70 cover plate I am now enabled to make one cylinder double-acting without increasing the number of sliding joints. I form upon the outside of the double-acting cylinder two simple passages or conduits, by which 75 fluid may be conveyed from the annular inlet and outlet ports at the end of the cylinder closed by the cover to the inlet and outlet openings respectively in the central valve structure.

80 With the above mentioned purpose of ready assembly I form upon the single acting cylinder a flange to which the cover of the double-acting cylinder is secured. A single set of studs is thus made to serve to 85 hold the cover upon the double-acting cylinder, to hold the double-acting cylinder upon the single-acting cylinder, and to grip the valve structure between the cylinders. These and other features of my invention 90 will be found described in detail hereinafter and pointed out in the appended claims.

Two embodiments of the invention are shown in the annexed drawings in which—

95 Figure 1 is a longitudinal section of a treble-acting vertical compressor constructed in accordance with the invention.

Fig. 2 is a plan, and

Fig. 3 a vertical section of the junction member or ring of the valve structure.

100 Fig. 4 is a plan from underneath of the cover closing the double-acting cylinder.

Fig. 5 is a longitudinal section of the second embodiment of the invention.

105 The pump of Figs. 1 to 4 comprises co-axial cylinders 3 and 4 respectively containing pistons 1 and 6 which are connected together by a piston rod 7. Both pistons are driven through a connecting rod 2 attached to the piston 1, and designed to be operated 110 by power from a shaft 37, which may carry a fly-wheel, through a crank 38. The single-

acting cylinder 3 is formed in one with a crank casing 62 to which access may be had through an inspection door 63. The double-acting cylinder 4 is closed at its top by the 5 cover or cap 61. Between the cylinders 3 and 4 there is located a valve structure formed in two main portions. The inner or ported members are built upon a casting 45 interposed between cylinders 3 and 4. Out- 10 let valves consisting of rings 55, 56 of der- matin, woodite, sheet metal or the like, are secured upon this casting by the lips of brass bosses 8^a and 8^b, which are screwed one into the other from opposite sides of the casting. 15 In this construction the outlet valves 55 and 56 seat upon the edge of the cylinders 3 and 4. Annular seatings 51 and 52 for the inlet valve are formed upon the bosses 8^a and 8^b. Disk inlet valves 12 and 13 of simi- 20 lar material to the outlet valves are held upon these seatings by means of a flanged brass sleeve 53 fitting the piston rod 7 and a collar 54 screwed upon it. The valve 12 is gripped between the flange of the sleeve 25 53 and the boss 8^b and the valve 13 is similarly gripped between the collar 54 and the boss 8^a. The outer part of the valve structure is a junction member or ring 46, the construction of which is more fully seen in Figs. 30 2 and 3. This is designed to complete with the inner ported members and the cylinders as direct and unrestricted channels as possible between the inlet and outlet valves and lateral inlet and outlet openings respectively. 35 In this construction of pump the upper cylinder 4 is intended to be double-acting. A second set of valves is, therefore, provided at its top. A ring 60, corresponding to one half of the casting 45, is secured be- 40 tween the cover 61 and the cylinder and carries an outlet valve 64 seating upon the end of the cylinder. This valve is retained in position by the lip of a boss substantially similar to 8^a or 8^b, which forms also the 45 seating for the inlet valve 59, and this valve in turn is held upon the seating by a boss 58 secured upon the cover.

Integral with the cylinder 4 there is formed a simple casting 39 the interior of 50 which is divided by a diametral partition 76 so that it forms two simple channels 40 and 41, of which the former serves as an inlet space and the latter as a delivery or outlet space. Around the ends of the cylinder 4 are formed outlet channels 49, 57, by 55 which the ports closed by the valves 56 and 64 respectively are connected with the outlet space 41. A similar channel 50, at the end of the cylinder 3, connects the outlet 60 port controlled by valve 55 with the space to the left of the wall 47 in the junction member 46. The inlet valve 59 connects through the inlet space 40, and the inlet valves 12 and 13 through the passages 48, 65 with the inlet opening in the ring 46.

The assembly of the valve structures has already been sufficiently indicated. The assembly of the whole pump is effected by a pair of studs 43, 44, which pass through the outlet and inlet spaces respectively and through 70 the junction member 46, and which secure the cover 61 of the double-acting cylinder to the flange 42 of the single-acting cylinder. Between these two members the studs secure in position the double-acting cylinder and the 75 valve structures.

In the modification shown in Fig. 5, so far as the parts correspond with those of the structure shown in Fig. 1, they are distinguished by corresponding references with 80 the prime mark attached. This modification is a horizontal double-acting pump, shown as operable by hand through a handle 65' which can be inserted in a socket 66' pivoted at 68' and joined to the connecting 85 rod 2' at 67'. The valve structure is still located between the cylinders and is still formed in two main portions, namely an outer junction member 69' and an inner ported structure carrying inlet and outlet 90 valves for both cylinders. This structure has coned surfaces 70', 71' which make joint with the junction member 69'. The inlet and outlet valves are not in this instance concentric, but are still co-axial and are of 95 the same construction as before. The casting 45' is still held between the two cylinders and still provides partition walls between the inlet and outlet ports. It is in this instance constructed in two portions, between which 100 is gripped a member fitting the piston rod 7' and having guards 74', 75' which retain in place upon the casting 45' the outlet valves 55', 56'. The inlet valves 12' and 13' are retained upon the casting 45' by 105 guards 72', 73' which screw upon its ends.

What I claim is: —

1. A pump or compressor comprising in combination a pair of cylinders in axial alignment a concentric jacket surrounding the leading cylinder, a diametric partition in said jacket dividing the same internally into two spaces, an inlet connection to one of said spaces, and an outlet connection to the other of said spaces, a valve casting uniting said cylinders, valves in said valve casting controlling the inlet to and the delivery from said cylinders, pistons in said cylinders, a piston rod connecting said pistons, a crank shaft journaled in the casting of the following cylinder beyond the working space thereof, a crank secured to said shaft, and rod connecting the following piston with said crank. 115

2. A pump or compressor comprising in combination a pair of vertical cylinders in axial alignment, a concentric jacket surrounding the upper cylinder, a diametric partition in said jacket dividing the same internally into two spaces, an inlet connec- 120

tion to one of said spaces and an outlet connection to the other of said spaces, a valve casting uniting said cylinders, valves in said valve casting controlling the inlet to 5 and the delivery from said cylinders, pistons in said cylinders, a piston rod connecting said pistons, a crank shaft journaled in the casting of the lower cylinder below the working space thereof, a crank secured to 10 said shaft, and a rod connecting the lower piston with said crank.

3. In a pump the combination of two co-axial cylinders, pistons in said cylinders, a piston rod joining said pistons, and a valve 15 structure located between said cylinders, said valve structure comprising inner ported members carrying inlet and outlet valves for each cylinder and a surrounding union member completing with said ported members 20 channels connecting said inlet and outlet valves respectively with inlet and outlet openings.

4. In a pump or compressor the combination of two co-axial cylinders, pistons moving 25 therein, a piston rod joining said pistons, and a valve structure located between said cylinders, said valve structure comprising inner ported members having co-axial annular valves closing inlet and outlet ports 30 for each cylinder separated by partition walls, and an outer union member surrounding said ported member and making joint with the partition walls thereof so as to complete channels from said annular inlet 35 and outlet ports to inlet and outlet openings respectively.

5. In a pump or compressor the combination of a cylinder, a flange formed upon the 40 end of the cylinder, a valve structure seated upon and making joint with said cylinder and its flange and carrying inlet and outlet valves for said cylinder and also a second set of inlet and outlet valves, a second cylinder seated upon and making joint with said 45 valve structure so that said second set of valves gives ingress into and egress from

it, a cover for the end of said second cylinder, studs and nuts securing said cover to the flange of said first cylinder and securing the valve structure and second cylinder 50 between said cover and flange, pistons in said cylinders, and a piston rod joining said pistons.

6. In a pump or compressor the combination with a cylinder, of a valve structure 55 seated upon and making joint with said cylinder carrying inlet and outlet valves for said cylinder and also a second set of inlet and outlet valves and having inlet and outlet openings connecting with said inlet 60 and outlet valves respectively, a second cylinder seated upon said valve structure so that the second set of valves therein gives ingress into and egress from said second cylinder at one end thereof, a second valve 65 structure carrying inlet and outlet valves at the other end of said cylinder, and an outer casting integral with said cylinder and having separate channels therein connecting the inlet and outlet valves of said 70 second valve structure with the inlet and outlet openings of said first valve structure.

7. In a pump or compressor the combination with a single-acting cylinder of a double-acting cylinder co-axial therewith, 75 a valve structure located between said cylinders common to both of them having inlet and outlet openings, a second valve structure at the other end of said double-acting cylinder, and a casting integral with said 80 double-acting cylinder having separate passages formed therein connecting the inlet and outlet valves of said second valve structure with the inlet and outlet openings of said first valve structure respectively. 85

In testimony whereof I sign my name to this specification in the presence of two subscribing witnesses.

JEAN ZWICKY.
